UNITED STATES PATENT OFFICE.

GEORGE C. BECK, OF BEAVERCREEK, MINNESOTA.

REGISTER FOR POOL-TABLES.

No. 811,195.

Specification of Letters Patent.

Patented Jan. 30, 1906.

Application filed August 17, 1904. Serial No. 221,064.

To all whom it may concern:

Be it known that I, GEORGE C. BECK, of Beavercreek, in the county of Rock, State of Minnesota, have invented certain new and useful Improvements in Registers for Pool-Tables, of which the following is a specification.

In Letters Patent of the United States No. 732,503, issued to me June 30, 1903, and in Letters Patent No. 738,515, issued to me September 8, 1903, I have shown and described certain improvements in registers for pool-tables; and my present invention has for its object to improve and simplify the mechanism of my aforesaid patents.

In my present device I make use of mechanism to which the triangle used for setting up the balls on the table is connected, so that each time the triangle is used for setting up the balls a game will be counted upon the register.

The invention consists generally in the constructions and combinations hereinafter described, and particularly pointed out in the claims.

In the accompanying drawings, forming part of this specification, Figure 1 is a front elevation of a register embodying my invention. Fig. 2 is a transverse section through the registering mechanism on line 2 2 of Fig. 4. Fig. 3 is a front elevation of the registering mechanism, a portion of the dial being shown in position and a portion of it being broken away to show the interior mechanism. Fig. 4 is a front elevation of the registering mechanism with the dial and hand or pointer removed and with the parts in the position which they assume while the register is being operated. Fig. 5 is a view similar to Fig. 4, the parts being in the position which they assume at the end of the registering or counting operation. Fig. 6 is a detail section on line 6 6 of Fig. 5 looking in the direction of the arrow. Fig. 7 is a detail of the disk that moves the register-operating dog.

In the drawings, 2 represents a suitable casing in which the parts of the mechanism are arranged. This casing is preferably secured upon a hanger 3, that is usually secured to the ceiling of the room in which the device is located by a plate or casting 4. The casing 2 may be secured to the hanger by any suitable means. I have shown an upwardly-projecting rod 5, extending from the upper part of the casing and connected to the lower

end of the depending rod or hanger 3. The lower portion of the casing is similarly provided with a projection 6, to which a rod 7 is secured. This rod is provided at its lower end with an eye 8, through which the cord 9' passes that is connected to the triangle 9. A dial 10, having the numerals from "0" to "15" arranged thereon, is secured over the front of the casing 2 and serves to inclose the mechanism arranged in said casing. Arranged in the casing is a stud 11. This stud has mounted upon it a ratchet-wheel 12, and the hub of the wheel projects through an opening in the dial 10 and has the pointer 13 secured to it. A coil-spring 14 is connected to the hub of the wheel 12 and to the casing. As the ratchet-wheel is rotated this spring is wound up, and when the wheel is released the spring turns the ratchet-wheel and pointer, so as to bring the pointer opposite the zero-mark. (Shown in Fig. 1.) Arranged within the casing is a spring-dog 15, adapted to engage the teeth of the ratchet-wheel and prevent backward movement thereof. A cord 16 is connected to this dog and runs preferably through rings 17 and 18, secured to the ceiling of the room and terminates at a point near the cashier's desk. When the register has been operated to count fifteen games or any less number representing the total number of games played by any set of players, the cashier can by pulling the cord 16 release the ratchet-wheel 12 and permit the spring 14 to turn the pointer back to zero against the stoppin 13', located at that point.

I prefer to provide means in connection with the registering device which will prevent the ratchet-wheel from being turned to such an extent as to cause the pointer to pass beyond the highest number on the dial. For this purpose I provide upon the hub of the ratchet-wheel a loose plate 19. This plate is mounted so as to turn freely upon the hub of the wheel, and one end of the plate is of greater width than the other, as shown by dotted lines in Figs. 3, 4, and 5, so that while the plate is free to swing loosely upon the hub of the wheel it stands normally in the position shown in Fig. 3 of the drawings, with its upper end in contact with the under surface of the dog 15. The upper end of the plate is preferably turned over, so as to stand substantially at right angles to the main part of the plate, and this end of the plate rests normally against a stationary lug 20 upon the

inner wall of the casing. Upon the back of the ratchet-wheel are two lugs 22 and 23. (See dotted lines in Figs. 3, 4, and 5, also see Fig. 2.) The lug 23 is in such position that if the register is turned so as to carry the pointer beyond the number "15" (or whatever number is used as the highest number on the dial) the end of the plate 19 will pass under the end of the spring-dog 15 and raise said dog above the line of the teeth on the ratchet-wheel, and said dog will thus be prevented from engaging the ratchet-tooth, and when the operating-pawl is disengaged from the ratchet-wheel said wheel will be turned backward by the spring 14, and the dog 15 will then engage the next tooth on the wheel and the pointer will stand opposite the highest number on the dial. The position to which the plate 19 is turned for the purpose of preventing the dog 15 from engaging the ratchet-wheel is shown in Fig. 4 of the drawings. A stop 24 upon the inner surface of the casing is provided which prevents the ratchet-wheel and the plate 19 from being turned far enough to permit the dog 15 to drop back of the end of the plate.

For the purpose of operating the ratchet-wheel after each use of the triangle 9 I provide upon the rear of the casing 2 a wheel or disk 25. This wheel is preferably secured upon a stud 26 by means of a nut 27. The stud extends through the wall of the casing, and arranged upon the stud within the casing so as to turn therewith is a disk 28, having a small portion of its periphery bent upward to form a lug 29, having a shoulder 30. A bell-crank lever 31 is arranged centrally upon the disk 28, being secured in position by a screw 32. A coil-spring 33 surrounds this screw, and one end thereof engages the wall of the casing, and the other end engages one arm of the lever 31. (See Figs. 3, 4, and 5.) A dog 34 is pivoted to the long arm of the lever 31, and a spring 35, arranged upon the pivot of the dog and engaging a lug 36 upon said dog and also the projection 37 on the end of the lever, tends to throw the upper end of the dog toward the ratchet-wheel 12. (See Fig. 5.) An inclined lug 38 is arranged upon the inner surface of the casing 2 near the edge of the disk 28. (See Figs. 4 and 5.) An arm 39 extends radially from the wheel 25. A cord or chain 40 has one end secured to the periphery of the wheel and its other end secured to a coil-spring 41, the opposite end of the spring being connected to the lower end of the rod 7. The wheel 25 is provided with a notch 41' in its periphery, (see Fig. 4,) and a spring-latch 42 is arranged to engage said notch. (See Fig. 2.) In operating the device, the parts being in the position shown in Fig. 1, the triangle 9 is removed to the pool-table. In order to do this, the operator must draw out the cord 9' through the eye 8 on the lower end of the rod 7, thereby turning the rod 39

downward and turning the disk or wheel 25 upon its axis, winding the cord or chain 40 upon the periphery of the wheel and putting the spring 41 under tension. When the wheel 25 has been turned far enough, the notch 41' will be brought opposite the latch 42, and said latch will engage said notch and lock the wheel in this position with the spring under tension. This movement of the rod 39, which moves said rod from the position shown in Fig. 5 to that shown in Fig. 3, will also turn the disk 28 from the position shown in Fig. 5 to the position shown in Fig. 3, carrying the lug 29 on said disk to the other side of the short arm of the bell-crank lever 31. A cord 45 is connected to the latch 42 and hangs downward therefrom. If preferred, the ends of this cord may be provided with a ring 46, and the cord 9' may extend through this ring: (See Fig. 1.) When it is desired to register a game, the attendant releases the latch 42 by pulling on the cord 45. The spring 41 now turns the wheel 25, thereby turning the disk 28 and causing the shoulder 30 on the lug 29 to engage the short arm of the bell-crank lever 31. This movement causes the dog 34 to engage one of the teeth of the ratchet-wheel and turn said wheel one notch, the parts traveling from the position shown in Fig. 5 to that shown in Fig. 4. The end of the short arm of the lever 31 engages the inclined lug 38, and riding up the inclined surface of said lug this end of the lever is caused to clear the lug 29 on the disk 28. Said lever is thereby released, and the spring 33 immediately moves said lever and the dog 34 from the position shown in Fig. 4 to that shown in Fig. 5. The ratchet-wheel will by this means be turned a distance equal to one notch upon its circumference, and the pointer 13 will pass from one figure on the dial to the next one. By repeating this operation when each game is played the register will show the number of games played by each set of players. When fifteen games have been played, or if any set of players stop using the table after having played a less number of games than fifteen, the cashier can reset the register at zero by pulling the cord 16. As it is sometimes desirable to have the cashier operate the register, I connect a cord 47 to one arm of the lever 31 and carry this cord also through the rings 17 and 18 to a point near the cashier's desk. (See Fig. 1.) I prefer to secure the end of this cord to the wall of the room or some other stationary object and I also prefer to connect a spring 48 to this cord and also to the ring 17. (See Fig. 1.) The use of the spring 48 prevents any undue strain upon the light spring 23, connected to the lever 31. The register herein shown and described is exceedingly simple in construction and mode of operation. It cannot be gotten out of order, it can be readily seen both by the players and the cashier, and by using this device 130

the proprietor has an absolute count of the number of games played upon each table and there can be no disputing the record.

I do not limit myself to the details of the construction herein shown and described, as the same may be modified in many particulars without departing from my invention.

I claim as my invention—

1. In a pool-table register, the combination, with a dial and a pointer, of a spring-actuated member, a pool-table triangle having a flexible connection with said member, means for locking said member against the tension of its spring at the limit of its movement in one direction, and a mechanism arranged to be set by such movement of said member for actuating said pointer when said member is released by the movement of said locking means.
2. In a pool-table register, the combination, with a dial and a pointer arranged to move over the same, of a spring-actuated ratchet-wheel upon the hub of which said pointer is secured, means for moving said wheel step by step in one direction, a dog 15 arranged to engage the teeth of said wheel and normally lock it against backward movement, a plate 19 loosely mounted on the hub of said wheel, a lug 22 carried by said wheel and adapted to engage said plate and move it under said dog to disengage the same from said teeth, and a lug 23 also arranged to engage said plate and return it to its normal position, substantially as described.
3. In a pool-table register, the combination, with a dial and a pointer arranged to move over the same, of a spring-actuated ratchet-wheel on the hub of which said pointer is secured, means for revolving said wheel to put said spring under tension, a dog 15 normally engaging the teeth of said wheel to prevent its backward movement, a loosely-mounted plate 19, lugs 20 and 24 between which said plate is movable, and means arranged to engage said plate and move it under said dog to disengage it from said teeth, substantially as described.
4. In a pool-table register, the combination, with a dial and a pointer arranged to move over the same, of a spring-actuated ratchet-wheel connected with said pointer, means for preventing backward movement of said wheel, a wheel 25 having a laterally-extending operating-arm 39, a pool-table triangle having a flexible connection with said rod, a spring connected with said wheel 25 and normally tending to hold said rod in its raised position, a latch 42 arranged to enter a notch provided in the wheel 25 and lock said rod in its depressed position, and mechanism set by the depression of said rod for actuating said ratchet-wheel when said latch is released, substantially as described.
5. In a pool-table register, the combination, with a dial and a pointer arranged to

move over the same, of a ratchet-wheel connected with said pointer, a wheel 25 provided with a radial rod 39, a triangle having a flexible connection with said rod, a spring connected with said wheel 25 and normally tending to hold said rod in its raised position, means for temporarily locking said rod in its depressed position, and means arranged to be set by the rotation of the wheel 25 and the depression of the rod 39 for moving said ratchet-wheel step by step when said locking means is released, substantially as described.

6. In a pool-table register, the combination, with a dial and a pointer arranged to move over the same, of a spring-actuated ratchet-wheel connected with said pointer, a pool-table triangle, an oscillating rod having a flexible connection with said triangle, a spring arranged to be put under tension by the movement of said rod in one direction, means for locking said rod at the limit of its movement in one direction, and a mechanism arranged to be set by such movement of said rod for actuating said ratchet-wheel step by step when said rod is released by the movement of said locking means.

7. In a pool-table register, the combination, with a dial and a movable pointer therefor, of an oscillating rod, a pool-table triangle having a flexible connection with said rod, a spring arranged to hold said rod in its normal inoperative position, locking means arranged to hold said rod at the limit of its movement in one direction against the tension of said spring, and mechanism set by such movement of said rod for actuating said pointer when said rod is released by the movement of said locking means.

8. In a pool-table register, the combination, with a dial and a pointer therefor, of an operating-rod, a pool-table triangle having a flexible connection with said rod, a wheel 25 having a notch in its periphery, a spring connected with said wheel and put under tension by the depression of said rod, a locking-latch arranged to enter said notch when said rod is depressed, and mechanism set by the depression of said rod for moving said pointer step by step when said wheel and rod are released by the operation of said locking means.

9. In a pool-table register, the combination, with a dial and a pointer arranged to move over the same, of a spring-actuated ratchet-wheel connected with said pointer, an operating-rod 39, a pool-table triangle having a flexible connection with said rod, a spring arranged to hold said rod in its raised position, a bell-crank lever 31 having means to engage the teeth of said ratchet, a disk 28 having a lug 29 arranged to be set by the depression of said rod 39 to engage said bell-crank and actuate it and said ratchet-wheel when said rod is released.

10. In a pool-table register, the combination, with a dial and a pointer arranged to

move over the same, of a spring-actuated ratchet-wheel connected with said pointer, a wheel 25 having a notch in its periphery, a spring connected with said wheel 25, a pool-table triangle operatively connected with said wheel 25, a locking-latch arranged to enter said notch, and mechanism set by the partial revolution of said wheel 25 for actuating said ratchet-wheel when said locking-latch is released, substantially as described.

11. In a pool-table register, the combination, with a dial and a pointer arranged to move over the same, of a spring-actuated ratchet connected with said pointer, a spring-actuated wheel 25, a pool-table triangle operatively connected with said wheel 25, means for locking said wheel 25 at the limit of its movement in one direction against the tension of its spring, and mechanism set by the

movement of said wheel in one direction for actuating said ratchet-wheel and pointer when said wheel returns to its normal position upon the disengagement of said locking means, substantially as described.

12. In a pool-table register, the combination, with a dial and a pointer, of a spring-actuated oscillating rod, a pool-table triangle having a flexible connection with said rod, means for locking said rod against the tension of its spring at the limit of its movement in one direction, and mechanism for actuating said pointer when said rod is released.

In witness whereof I have hereunto set my hand this 4th day of August, 1904.

GEORGE C. BECK.

In presence of—

FRANK E. WELKER,
HENRY L. NOWKA.
